Primary Examiner—Louis S. Zarfas*Assistant Examiner*—Eric Watterson*Attorney, Agent, or Firm*—Quarles & Brady[57] **CLAIM**

The ornamental design for a bidet, as shown and described.

DESCRIPTION

FIG. 1 is a left, top, front perspective view of a bidet embodying my new design;

FIG. 2 is a left side elevational view thereof, the right side elevational view being a mirror image of the left side shown;

FIG. 3 is a front elevational view thereof;

FIG. 4 is a top plan view thereof;

FIG. 5 is a rear elevational view thereof; and,

FIG. 6 is a bottom plan view thereof.

The broken line representations of holes in FIGS. 1 and 4 are for purposes of illustration only, and form no part of the claimed design.

The characteristic features of my design resides in design lines extending from the rear corners of the basin to the rear corners of the rim.
